DYE PACKAGE

Carl J. Russo, Newark, and Ewart H. Shattuck, Wilmington, Del., assignors to Joseph Bancroft & Sons Co., Wilmington, Del., a corporation of Delaware
Filed July 31, 1962, Ser. No. 213,629
12 Claims. (Cl. 28—21)

This invention relates to a yarn package suited for processing in standard dyeing equipment and more particularly to a package wherein the yarn is packed in the form of an annular mass in successive helical layers.

An object is to provide a package of the above type having novel and improved characteristics.

Another object is to provide a yarn package wherein the yarn is maintained under tensionless conditions during the processing step.

Another object is to provide suitable apparatus for making such a yarn package.

Various other objects and advantages will be apparent as the nature of the invention is more fully disclosed.

In accordance with the present invention the yarn is fed by suitable means such as by an air nozzle in the form of overlapped turns or coils into the annulus between an outer cylindrical can wall and an inner core tube. The can is rotated and advanced axially with respect to the nozzle so as to lay the yarn in a series of helical layers in the annulus. After filling the can is covered to retain the yarn and may be placed in a standard vat dyeing machine wherein treating fluid is passed through the mass of yarn. Due to the manner in which the yarn is laid in the can it is maintained tensionless and may adjust itself to any degree of shrinkage without increase in yarn tension. After processing the yarn may be withdrawn from the package and wound onto a spool or cop in the usual manner.

The nature of the invention will be better understood from the following description, taken in connection with the accompanying drawings in which a specific embodiment has been set forth for purposes of illustration.

In the drawings:

FIG. 1 is a side elevation of an apparatus embodying the invention with parts in section;

FIG. 2 is a partial vertical section taken on the line 2—2 of FIG. 1 but on a larger scale;

FIG. 3 is a partial sectional view of the apparatus of FIG. 1, but on a larger scale.

FIG. 4 is a partial horizontal section taken on the line 4—4 of FIG. 3;

FIG. 5 is a partial vertical section, similar to FIG. 3, but showing the parts in a different position;

FIG. 6 is a partial horizontal section taken on the line 6—6 of FIG. 5;

FIG. 7 is a detail view of the cover plate for the yarn package;

FIG. 8 is a partial sectional view of a yarn package embodying the invention;

FIG. 9 is a detail of the concentric retaining rings as used during the rewinding stage; and

FIG. 10 is a partial vertical section taken on line 10—10 of FIG. 4, but on a larger scale.

Referring to the drawings more in detail, the apparatus is shown as comprising a base plate 10 carrying a center post 12 and having a downwardly extending bracket 13 to which is secured to a motor 14. The motor 14 has a vertical shaft 15 carrying a sprocket 16 which is coupled by a chain 17 to a larger sprocket 18 pinned on a shaft 19 which is journaled in a boss 20 carried by the base plate 10. A support disc 26 has a hub 27 pinned to the shaft 19 and resting on a boss on the top of the base plate 10.

The support disc 26 has an annular recess 28 in which the lower beaded edge of an annular can wall 29 is seated. An extension wall 30 is formed with a bottom shoulder 31 fitting over the top edge of the can wall 29. The extension wall 30 carries a series of eyes 32 which are engaged by the top ends of spring hooks 33, the lower ends of which are adapted to hook into an annular groove 34 in the under side of the support disc 26 for securing the can wall 29 and the extension wall 30 in place on the disc 26.

10 A sleeve 38 is splined onto the shaft 19 for axial movement by roller bearings 39 riding in grooves 40 in the shaft 19 so that the sleeve 38 rotates with the shaft 19 but is slidably axially thereon. The sleeve 38 has a closed top end 41 which carries a swivel hook 42 for the purpose to be described. A core tube 43 carrying a bottom flange 44 fits over the sleeve 38 and is rotated therewith. The core tube 43 has perforations 45 and is adapted to form the inner core of the package. The bottom disc 44 has a sliding fit within the can wall 29 and is adapted to form the bottom of the finished package. The can wall 29 has perforations 46 for the passage of treating fluids through the package. In its lower position the disc 44 rests on the top surface of the support disc 26 and on the inturned 15 peripheral bead of the can wall 29. The core tube 43 carries at its upper end a ring 47 having a shoulder 48 on which a core tube extension 49 seats. The core tube extension 49 is removably mounted over the sleeve 38 with its upper end projecting slightly above the top of the extension wall 30.

An arm 55 is journalled between thrust bearings 56 and 57 carried by a sleeve 58 which is slidably mounted on the post 12. The sleeve 58 carries a rack 59 meshing with a pinion 60 journalled in ears 61 on the post 12. A 20 crank 62 is connected to turn the pinion 60 for raising and lowering the arm 55. The arm 55 carries a vertical bracket 65 having at its upper end a boss 66 in which is journalled a shaft 67 carrying at one end a feed roll 68 and at its other end a bevel gear 69. A cooperating 25 feed roll 70, shown in FIG. 2, is mounted on a shaft 71 journalled in a second boss 72 on the bracket 65. A vertical shaft 75 is journalled in a boss 76 on the arm 55 and carries at its upper end a bevel gear 77 meshing with the bevel gear 69. At its lower end the shaft 75 is journalled 30 in a boss 78 carried by the vertical bracket 65. The shaft 75 carries a pulley 79 and is connected to the armature shaft of a motor 80 which is mounted on a bracket 81 carried by the bracket 65.

35 A yarn tube 85 is carried by the arm 55 with its upper end adjacent the bite of the feed rolls 68 and 70 to receive the yarn therefrom. An air tube 86 communicates with the side of the yarn tube 85 in a direction to feed the yarn downwardly. A rotating feed tube 87 is journalled in a boss 88 on the bracket 65 in registration with the lower end of the yarn tube 86. The feed tube 87 carries a pulley 89 driven by a belt 90 from the pulley 79. The lower end of the feed tube 87 is curved to form a yarn discharge nozzle 92 extending outwardly at an angle of about 45 degrees from the axis of the tube. A split annular cover plate 95 is carried by a rod 96 from the arm 55. The cover plate 95 fits in the annulus between the core tube extension 49 and the side wall extension 30 and extends helically to conform to the pitch of the yarn layers to be laid in the annulus and to form a vertical opening 97 between the vertically displaced leading and trailing ends of the cover plate 95. The lower trailing end of the helical cover plate is cut away to form fingers 99 over which the yarn slides into the opening 97 in the manner to be described. The rod 96 may be adjusted in the arm 55 for adjusting the height of the cover plate with respect to the yarn tube 87. A series of pins 100 is carried

by the disc 44 to grip and distribute the yarn over the surface of the disc 44 at the beginning of the filling operation.

For space dyeing, the yarn as it is laid in the container, a dye housing 130 may be carried by the cover plate 95 at a point in advance of the fingers 99. The housing 130 may be divided by a wall 136 into two compartments 131 and 132 which communicate with the yarn annulus by a series of holes 133. Dye may be supplied to the chambers 131 and 132 through tubes 134 and 135 respectively, which lead to a source of dye, not shown. The same or different dyes may be supplied to the two chambers depending upon the effect desired.

A cop support 102 is carried by the bracket 65. This support carries a cop 103 from which yarn 104 is fed through eyes 105 to a trumpet 106 terminating adjacent the bite of the feed rolls 68 and 70.

The arm 55 extends beyond the post 12 and carries a boss 107 in which a rod 108 is adjustably secured by a set screw 109. The rod 108 carries at its lower end a U-shaped shoe 110 adapted to fit in the annulus between the core tube 49 and the can wall 30.

A counterweight 115 is hung from a cord 116 which passes over grooved rolls 117 carried by an arm 118 fixed to the post 12. The end of the cord 116 is attached to the swivel hook 42 so that the core tube and associated parts are held in their upper position by the counterweight 115.

An air tube 120 is connected to the air tube 86 and to a valve 121 mounted on a bracket 122 carried by the arm 55. An air supply pipe 123 is connected to the valve 121.

A cover plate 125, as shown in FIGS. 5 and 6, is adapted to be placed over the core tube extension 49 after the can has been filled and the helical cover 95 removed. The cover plate 125 carries a spring clip 126 which is adapted to snap into a groove 127 in the ring 47 to form a top closure for the can as shown in FIG. 8.

In setting up the above apparatus the can wall 29 with the core tube 43 and bottom disc 44 therein is placed on the support disc 26, the core tube extension 49 is placed over the sleeve 38 and seated on the core tube 43 and the extension wall 30 is seated over the can wall 29 and secured by the latches 33. The arm 55 is then turned to bring the helical cover 95 over the annulus between the can wall and the core tube and is brought into a position slightly below the top edges of the wall extension and the core tube extension. The cord 116 is then attached to the swivel hook 42 on the sleeve 38 so that the counterweight 115 raises the core tube until the bottom disc 44 with its pins 100 engages the under surface of the helical cover 95. The motor 80 is started to drive the feed rolls 68 and 70 and to rotate the feed yarn tube 87 and the air valve 121 is open to cause the yarn to be fed along the yarn tube 85 and to be discharged from the rotating nozzle 92 and laid in the form of a succession of overlapped loops on the fingers 99 of the helical cover 95. At the same time the motor 14 is started to cause slow rotation of the support disc 26 and of the can parts which are carried by the support disc. The yarn loops are projected into the opening 97 in the helical cover 95 and are also carried by the pins 100 through the opening 97 and under the helical cover 95. The pins 100 may of course be replaced by other types of friction surfaces which would strip the yarn from the fingers 99. The layer of yarn thus laid is compacted by the helical cover 95 as it advances and is progressively depressed by the contour of the cover to lower the disc 44 against the force of the counterweight 115. The pressure of the layer of yarn against the helical plate is adapted to depress the core member and the bottom member against the force of the counterweights for laying the layer of loops in the form of a helix extending from the top to the bottom of the annular space.

For space dyeing, dye is supplied through the tubes 134 and 135 to the chambers 131 and 132 and through

the holes 133 in the cover plate 95 at a rate to impregnate at least the surface layer of yarn. When the yarn package is treated to set the dye a random variation in effect is obtained. This effect is enhanced by supplying different dyes through the tube chambers 131 and 132. A uniform effect may be produced by supplying the dye at a rate to impregnate the yarn uniformly throughout the cross-section of the yarn layer. Successive layers of the yarn are laid in the form of a helix in the annulus until the can is filled and the bottom disc 44 is brought into contact with the support disc 26. At this point automatic stop means may be provided to stop the operation of the motors. Such stop means may be controlled, for example, by the position of the counterweights 115.

At this point the operation is stopped, the arm 55 raised to lift the helical cover 95 from the can. A cover ring 125 (FIG. 7) is then placed over the yarn, the arm 55 turned to bring the shoe 110 over the plate 125 and lowered to depress and compact the yarn until the spring clip 126 on the cover plate 125 snaps into the groove 127 in the core tube ring 47. The cover plate is thus locked in place to close the package. The shoe 110 is then withdrawn, the core tube extension 49 removed and the latches 33 released and the wall extension 30 removed to leave the can consisting of the wall 29, core tube 43, bottom disc 44, and cover plate 125 with the compacted yarn in the annulus therebetween, as shown in FIG. 8.

The yarn package may now be processed in a vat dyeing apparatus of standard type adapted to force a treating fluid through the package. During this processing the yarn is in tensionless state and is free to shrink without introducing tension.

After processing the cover plate 125 may be removed and replaced by a pair of concentric rings 137 as shown in FIG. 9 adapted to hold the yarn compacted and to form an annular space therebetween through which the yarn can be removed for rewinding. The concentric rings hold the yarn in compacted state during the withdrawal from the package and prevent the yarn from tangling or knotting as it is withdrawn.

What is claimed is:

1. Apparatus for packaging yarn which comprises a rotatable support disc carrying a central spindle, a sleeve 45 keyed to said spindle for relative axial movement while rotating therewith, a peripheral can wall releasably held on said support disc, a core tube carrying a bottom member seated on said sleeve and forming with said peripheral can wall an annular yarn space, a helical cover plate having an 50 opening to receive yarn disposed within said peripheral wall, yieldable means holding said core tube with its bottom member in raised position with the bottom member adjacent the underside of said plate, means feeding said yarn through said opening onto said bottom member in the form of overlapping and advancing coils to form a 55 layer, means for rotating said bottom member to lay the layer in said annular space, the pressure of the layer of yarn against said helical plate being adapted to depress said core member and said bottom member against the force of said yieldable means for laying said layer in the form of a helix extending from the top to the bottom of said annular space.

2. Apparatus as set forth in claim 1 including a cylindrical member adapted to seat on said peripheral can wall to form an extension thereof, means clamping said cylindrical member to said support disc and an extension core tube adapted to seat on said support disc and an extension core tube adapted to seat on said first core tube to form with said cylindrical member an extension of said annular space.

3. Apparatus for packaging yarn in a container having an annular space to receive said yarn, which comprises a rotatable support disc carrying said container, a vertical post, an arm journalled to turn on said post, a rotatable yarn tube journalled on said arm in a position to register with said annular space in said container and terminat-

ing in an inclined nozzle adapted to lay the yarn in horizontal coils as it turns, driven feed rolls adapted to feed said yarn to said yarn tube at a predetermined rate, means supplying air to said nozzle to facilitate the feeding of the yarn therefrom, and means rotating said support disc for laying the coils of yarn in overlapping and advancing relationship in the form of a helically wound layer in said container.

4. Apparatus as set forth in claim 3 having means for adjusting the axial position of said arm on said post for thereby adjusting the position of said yarn tube with respect to said container.

5. Apparatus as set forth in claim 3 in which said arm extends on opposite sides of said post and carries a pressure shoe in a position to be brought into registration with the yarn package when said yarn tube is retracted therefrom.

6. Apparatus for forming a yarn package comprising a rotatable bottom member adapted to receive said package and a central core tube disposed axially of said bottom member, a cover member disposed around said core tube and spaced from said bottom member to form therewith an annular space around said core tube in which the package is to be laid and having an opening through which the yarn is to be fed into said annular space, said bottom member being shiftable axially relative to said cover member due to the pressure of the yarn for increasing the axial length of said annular space as the yarn package builds up therein and having means to maintain axial pressure on said package, means feeding said yarn in successive loops through said opening into said annular space to be advanced due to the rotation of said bottom member in a series of helically wound layers each of which is composed of a succession of overlapped loops.

7. Apparatus as set forth in claim 6 wherein the yarn feed means comprises a rotatable nozzle having air supply means to facilitate the feeding of the yarn from said nozzle and means feeding the yarn to said nozzle at a predetermined rate.

8. Apparatus as set forth in claim 7 in which said bot-

tom member is provided with upstanding pins adapted to grip the yarn as it is laid thereon from said rotating nozzle.

9. Apparatus as set forth in claim 6 in which said cover member is helical in form to conform to the helical layers of said package and is provided with leading and trailing ends spaced vertically to form an opening therebetween to receive said yarn loops, said trailing end including fingers adapted to receive said loops from said feed means and to guide the same into said opening.

10. Apparatus as set forth in claim 6 in which said cover member is helical in form to conform to the helical layers of said package.

11. Apparatus as set forth in claim 10 in which said helical cover member carries means for applying a dye to said yarn.

12. Apparatus as set forth in claim 10 in which said helical cover member is formed with dye openings and means is provided for feeding a dye through said openings onto said yarn.
